RUN REPAIRING NEEDLE

Edmond Lalanne and Pierre Grandjean,
Marseilles, France

Application January 3, 1946, Serial No. 638,756

7 Claims. (Cl. 66—117)

1

The present invention relates to a needle for making up knitted materials and repairing same (taking up stitches).

For that kind of materials, and especially for those used in the manufacture of ladies' stockings, there are known needles used for taking up stitches, but these needles necessarily possess mechanical parts that are very fragile because of their small size, and are for that reason all liable to numerous disadvantages and stoppages, and sometimes they even cut the stitches or tear the material to be repaired and render it quite useless, whereas of course their object is to put damaged knitted material into order again.

All those causes of accidents, well known by the users of these appliances, can be abolished by the needle subject matter of this invention.

This needle, the basic principle of which excludes springs, makes the stitch with the help of a single oscillating cam.

According to the drawings:

Fig. 1 gives a large scale side view of the oscillating cam needle as well as a longitudinal section of same.

Fig. 2 gives a plan of the needle depicted on Fig. 6.

Figs. 3, 4 and 5 illustrate the working of the oscillating cam while making a mesh at different periods and drawn the same way as Fig. 1.

The needle according to the present invention consists of a body 9 the cross section of which looks like a suitably flattened tube with an empty space the inside width of which is sufficient for the fitting of a cam 10, so weighted that its weight alone is sufficient to bring it back to its position of rest, Figs. 1 and 3. The said cam is the main operating member and principal feature of this invention.

One of the ends of the body 9 is bent over in order to form the hook 11 with the opening 12 enabling the entry of a thread on this hook. The other end of body 9 is shaped in the usual way for handling.

Cam 10 oscillates round trunnion 13 and has in its profile a first projection 14 which protrudes into the curve of the hook and takes the pressure of a thread forming half a stitch and it possesses also an inclined surface 15 on which slides a second thread forming another half stitch in which the first one must penetrate in the usual way, surface 15 being extended in the general direction of the hook to provide a second projection 15' of the cam 10 adapted to overlie the point of the hook.

2

The needle built as described, and according to principles which are considered new, works as follows:

Hook 11 entering the material pushes apart the stitches formed by threads 3 and 4, see Figs. 3, 4, and 5. Thus the pull on the needle in the direction of the arrows A causes thread 3, Fig. 3, to follow body 9 and the inclined side of opening 12, thus entering the hook and coming in contact with first projection 14 of cam 10; the contact of the thread and the slight pressure exerted causes cam 10 to swing on its trunnion 13, position shown on Fig. 4; this motion, see Fig. 4, causes the inclined portion 15 to start on its way out of opening 12 in order to catch and guide thread 4, thus avoiding its passing into hook 11. This movement also causes second projection 15' to cover point 6. The pull of thread on first projection 14 continuing, cam 10 pursues its motion until thread 3 hits the bottom 6a of hook 11, see Fig. 5. At that moment thread 4 which is not influenced by the pull on the needle passes over thread 3 thus forming a stitch, it being well understood that threads 3 and 4 each go to make up half a stitch.

In the above position, see Fig. 5, we must especially consider the fact that the third projection 16 of cam 10 hits the inside of body 9 squarely, and that point 6 of hook 11 never gets into contact with cam 10 protecting it, the hook therefore not receiving any shock, whatever the speed of the working of the needle and the subsequent motion of the cam 10 may be. The needle can thus be worked to the best advantage.

The result described above shows a very great improvement on the needles in use at present, none of which can show a hook protected in such and effective way.

We must also consider the fact that this needle works without the help of any spring, which simplifies its manufacture and lengthens its life as it has the smallest possible number of parts, that it cannot get out of order and that its design gives it remarkable strength, which is not the case for other known needles which are very fragile because their parts lack strength. The main feature of this invention rests therefore on the advantages described above and in the use of a cam with very small angular displacement.

Having now particularly described and ascertained the nature of our said invention, an embodiment of which is shown as non-limitative example in the accompanying drawings and

which may be carried out in other ways not shown without thereby departing from the spirit and scope of the invention, what we claim is:

1. A needle for making and repairing knitted material comprising a tubular body having a curved closed end and an aperture adjacent said end having one side inclined inwardly toward said closed end and toward the longitudinal axis of said body, and the other side constituting a curved hook opening away from said closed end, and an oscillating member located inside said body having a first projection adapted to protrude in the curve of said hook, an inclined portion adapted to project beyond the inclined side of said aperture, and a second projection between said first projection and said inclined portion adapted to obturate the opening and outwardly overlie said hook.

2. A needle as claimed in claim 1 wherein said body has a flattened cross-section having two straight sides and two curved parts joining said straight sides, said aperture being in one of said curved parts.

3. A needle as claimed in claim 1 wherein said oscillating member pivots on a trunnion fixed transversely of said body.

4. A needle as claimed in claim 1 wherein said oscillating member has a third projection adapted to abut against said body as soon as said second projection obturates the opening of said hook thereby to prevent said member from making contact with the point of said hook.

5. A needle as claimed in claim 4 wherein said oscillating member pivots on a trunnion traversing said member at a point spaced from the center of gravity of said member.

6. A needle for making and repairing knitted material comprising a substantially tubular body having a curved closed end and an aperture ad-

5 jacent said end, the side of said aperture remote from said closed end being disposed at an angle to the longitudinal axis of said tubular body and inclined inwardly in direction and the side of said aperture adjacent said closed end being undercut and curved to form a hook, including a point directed toward said aperture and an oscillating cam located inside said body having a first projection adapted to be engaged and displaced by a first thread forming a half stitch before said thread engages the bottom of said hook, an inclined portion adapted, when said first projection is displaced, to engage a second thread forming a half stitch, said portion being inclined at an angle oppositely to the inclined side of said aperture, a second projection adapted to overlie and to obturate said hook when said first projection is displaced by a thread, and a heel adapted to abut against the interior wall of said body thereby to prevent said oscillating portion from contacting the point of said hook.

7. A needle as claimed in claim 6 wherein said oscillating cam is pivoted on a trunnion fixed transversely of said body and traversing said cam at a point located between the center of gravity of said cam and said hook.
